BOX FOR SMOKE DETECTORS

William Finkelstein, Baltimore, Md., assignor to Universal Security Instruments, Inc., Baltimore, Md.

Filed Apr. 2, 1974, Ser. No. 457,162

Term of patent 14 years

Int. Cl. D9—03

U.S. Cl. D9—197

FIG. 1 is a front perspective view of a box for smoke detectors showing my new design; and

FIG. 2 is an exploded front perspective view thereof showing the end opposite that seen in FIG. 1.

The side opposite that seen is the same in appearance as the side shown.

I claim:

The ornamental design for a box for smoke detectors, substantially as shown and described.
